UNITED STATES PATENT OFFICE

WILLIAM S. THOMAS, OF LINDEN, NEW JERSEY, ASSIGNOR TO THOMAS SPARK PLUG COMPANY, OF ROSELLE PARK, NEW JERSEY.

INSULATED ELECTRODE STRUCTURE FOR SPARK PLUGS.

Application filed January 4, 1922. Serial No. 528,870.

To all whom it may concern:

Be it known that I, WILLIAM S. THOMAS, a citizen of the United States, residing at Linden, in the county of Union and State 5 of New Jersey, have invented certain new and useful Improvements in Insulated Electrode Structures for Spark Plugs, of which the following is a specification.

One object of my present invention is to 10 provide an improved structure which will more effectively insulate a spark plug electrode and prevent the insulating means from becoming impaired by heat, products of combustion, oils or moisture; thus prolonging 15 the life of the plug and preventing current leakage.

Another object is to so construct my improved electrode structure that it can be readily manufactured and will keep comparatively 20 cool while in use.

These objects, and other advantageous ends which will be described hereinafter, I attain in the following manner, reference being had to the accompanying drawing in 25 which—

Figure 1 is an elevation of an insulated spark plug electrode made in accordance with my invention.

Figure 2 is a central longitudinal section 30 of said insulated electrode,

Figure 3 is a transverse section taken on the line 3—3 of Figure 1,

Figure 4 is an elevation, partly in section, of a portion of the electrode rod,

Figure 5 is an elevation of another portion 35 of said rod, and

Figure 6 is an inverted plan view of a cap portion which I preferably employ.

Referring to the drawing, 7 represents an 40 insulator body portion which can be made of porcelain or other material which is a non-conductor of electricity and which will withstand heat without becoming impaired to such extent as to interfere with its use as 45 an insulator. The body portion 7 includes an annular boss or flange 8 which projects laterally therefrom and is positioned between the upper and lower ends. This boss is provided for the purpose of securing the 50 insulator electrode within a shell or jacket (not illustrated) in any suitable manner, such for example as by means previously employed for securing electrode insulators within the metallic jackets which are ordi-

narily screwed into the cylinders of internal 55 combustion engines. The body portion 7 includes a stem 9 which depends below the flange 8 and an upwardly extending portion 10 which projects above said flange 8. Furthermore the body portion 7 includes a 60 cavity 11 which is preferably cylindrical and extends downward from the top surface 12 of the portion 10 to a position having its bottom surface 13 below the flange 8 and within the stem 9. The recess 14 extends 65 upward from the bottom surface 15 and the inner end 16 of the recess is positioned below the bottom surface 13 of the cavity 11 so as to provide a partition 17 between the bottom 70 of the cavity and the inner end 16 of the recess. This partition has an axial hole 18 therein for a purpose hereinafter described. It will be understood however that the hole 18 is of small diameter compared to the 75 diameter of the cavity 11 and recess 14.

An electrode rod includes two sections 19 and 20. The section 19 at its lower end includes an annular upturned flange 21 which is spaced from the main part 22 so as to produce an annular channel or groove 23. 80 Thus the flange 21 actually provides a cup open at the top surrounding the main part 22 as clearly illustrated in Figures 2 and 4. A screw threaded hole 24 extends axially upward from the bottom surface 25 of the 85 rod section 19 and the upper end of the main part 22 of said rod section is externally screw threaded as shown at 26. The rod section 20 includes a screw threaded portion 27 which is adapted to be projected upward 90 from the hole 18 and engage the screw threaded hole 24 of the rod section 19; said rod section 19 being positioned within the cavity 11 with the flange 21 lowermost and it is preferable to insert a gasket or washer 95 28 between the surface 25 of the rod section 19 and the bottom surface 13 of the cavity 11. The rod section 20 includes an angular 100 enlargement 29 which is preferably made in the form of a nut and a washer or gasket 100 30 is placed over the portion 27 to abut the angular portion 29 and the inner surface 15 of the recess. The rod portion 29 also includes a depending part 31 which projects through the recess 14 and serves as the 105 sparking part of the electrode rod. It will be noted that by turning the section 20 relative to the section 19 that pressure will

be brought to bear upon the partition 17 and thus securely hold the rod to the body portion 7.

A mica tube 32 is entirely embedded with-
5 in a housing or shell 33 of glass or other vitreous material which is impervious to water, oil, products of combustion or gases which are encountered for example in connection with the explosion within internal combustion engines and the housing 33 is prefer-
10 ably molded integrally around the mica tube 32. The internal diameter of the housing 33 is such as to permit the rod section 19 to extend therethrough; the construction
15 further being such as to allow the lower end of the housing to set within the channel 23 which is provided by the flange 21 and main part 22 of the electrode rod section 19. Furthermore the arrangement is preferably
20 such as to allow an annular space 34 to exist between the outer surface of the housing and the inner side wall of the cavity 11; said space extending downward from the top surface 12 of the body portion to a position be-
25 low the bottom of the flange 8 as clearly shown in Figure 2.

A cap or cover 35 has a depending flange 36 adapted to surround the upper part of the portion 10 and said cap has a hole 37 through which the upper screw threaded end 26 of the electrode rod section 19 extends. The cap flange 36 has grooves 38 at spaced distances apart which extend upward from the bottom surface 39 of the cap to the inner surface 40 of said cap; said inner surface being positioned above the surface 18 of the body portion so as to provide a space 41. Lugs 42 which depend from the surface 40 are adapted to engage the top surface 12 of the body portion 7.

A binding nut 43 is screwed on the end 26 of the rod section 19 and is adapted to engage the top surface 44 of the cap. Thus by turning down on the nut 43, the cap will be held in firm contact with the top surface 12 of the body portion 7 since said action will be resisted by the angular or nut portion 29 and gasket 30 of the rod section 20. It will be noted that such structure as above described includes a mica tube which extends from the position above the flange 8 to a position below the flange 8 and will be capable of intercepting any transverse attempt of current leakage and furthermore this tube of mica is so covered that it will not be affected so as to lose its good qualities as an insulating member; said qualities only existing when the mica tube is kept free from contamination with moisture, gases, oils or products of combustion.

It will be further noted that said structure allows air to surround the housed mica tube and thus the tube is kept ventilated and comparatively cool; the air being free to pass be-
65 tween the atmosphere and the spaces 34

through the medium of the grooves 38 and space 41. The parts of my improved structure can be readily assembled and disassembled. The housed mica tube can be placed within the electrode rod section 19 before the latter is placed within the cavity 11 and it is merely necessary to insert the part 27 of the portion 20 of the rod upward through the hole 18, after which the part 20 can be rotated by inserting a small socket wrench within the recess 14 so as to engage and rotate the nut portion 29. The cap can then be slipped over the top of the section 19 and the nut 43 applied. Any desirable clamping nuts for electric conduit wire can be connected to the end 26.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A structure of the class described including a body having a cavity formed therein, an insulating tube confined within the cavity, an electrode rod taken through the body and through the insulating tube and having an exterior thread bearing portion, a member adapted for threaded engagement with the thread bearing exterior portion and having a flange surrounding the adjacent end portion of the body and provided with grooves in spaced relation extending upwardly from the bottom edge of the flange, and projections on said member adapted to rest upon the adjacent edge of the body supporting the member in spaced relation with respect thereto.

2. A structure of the class described including a body having a cavity, an electrode rod extending into the cavity and comprising sections in threaded connection, one of the sections having screw threads formed in its outer end portion, a housing having a tube of insulating material confined therein, surrounding one of the electrode sections and supported thereby in spaced relation to the walls of the cavity, a cap for the body having portions in spaced relation with the walls thereof and having a central opening for the passage of the threaded portion of the electrode section, and a member threaded on the threaded electrode section to hold the contacting portions of the cap firmly in contact with the body.

3. A structure of the class described including a body having a cavity, a cap for the body having portions in spaced relation to the body, an electrode rod extending into

- the cavity and through the cap, and a housing encasing a mica tube carried by the electrode rod in spaced relation with the walls of the cavity.
5. 4. A spark plug electrode structure including a body portion having a cavity; an electrode rod secured to said body portion and extending through said cavity; and a cap having a flange surrounding said body portion adjacent its top and being grooved to provide an air passage between it and the body portion, said cap having lugs spaced apart to provide a space communicating with said cavity and with said grooves; substantially as described.
10. 5. A spark plug electrode structure including a body portion having a cavity; an electrode rod secured to said body portion and extending through said cavity; a cap having a flange surrounding said body portion adjacent its top and being grooved to provide an air passage between it and the body portion, said cap having lugs spaced apart to provide a space communicating with said cavity and with said grooves; substantially as described.
15. 6. A spark plug electrode structure including a body portion having a cavity; an electrode rod secured to said body portion and extending through said cavity; a cap having a flange surrounding said body portion adjacent its top and being grooved to provide an air passage between it and the body portion, said cap having lugs spaced apart to provide a space communicating with said cavity and with said grooves, said rod having a screw threaded portion extending through said cap; and a nut in engagement with said screw threaded portion adapted to hold the cap in position relatively to said body portion; substantially as described.
- In testimony whereof I have signed my name to this specification in the presence of a subscribing witness.

WILLIAM S. THOMAS.
